UNITED STATES PATENT OFFICE.

CARL ILIGAN, OF CORONA, NEW YORK.

COLLARET.

1,192,900.

Specification of Letters Patent. Patented Aug. 1, 1916.

Application filed July 15, 1915. Serial No. 39,945.

To all whom it may concern:

Be it known that I, CARL ILIGAN, a subject of the Emperor of Germany, and residing at Corona, Long Island, in the county of 5 Queens and State of New York, have invented certain new and useful Improvements in Collarets, of which the following is a specification such as will enable those skilled in the art to which it appertains to 10 make and use the same.

This invention relates to what are known as collarets or facings for gentlemen's vests, ladies' coats and similar garments, and the object thereof is to provide an improved 15 device of this class which is simple in construction and can be quickly and easily attached to, or detached from the garment whenever desired.

The invention is fully disclosed in the following specification, of which the accompanying drawing forms a part, in which the separate parts of my improvement are designated by suitable reference characters in each of the views, and in which:—

25 Figure 1 is a view showing my improved collaret, or a part thereof, and the method of attaching it to a garment; Fig. 2 a transverse sectional view showing diagrammatically the separate parts of the collaret; Fig. 30 3 a transverse section of the collaret only on the line 3—3 of Fig. 1; and, Fig. 4 a sectional view showing in detail the means for and method of connecting a collaret with a garment.

35 In the drawing forming part of this specification, I have shown at *a* the front part of one side portion of a garment and at *b* my improved collaret connected therewith.

The collaret is composed of two separate 40 longitudinal strips *b*² folded centrally as shown in Figs. 2 and 3, and these strips *b*² are composed of silk or any other suitable material, and are provided with inner linings *b*³, and the edges of the strips *b*² are 45 folded inwardly over the edges of the linings, as shown at *b*⁴.

Placed in the folded parts or strips *b*² is a central reinforcing and connecting strip *b*⁵ which extends longitudinally through the 50 collaret, and the separate parts of the collaret are stitched together and to the strip *b*⁵ by a longitudinal row of stitches *b*⁶ at each side of a central longitudinal space *b*⁷ formed on each side of the collaret by the 55 folding of the strips *b*², as clearly shown in Figs. 1 and 3.

In attaching my improved collaret to the garment I provide pin devices *c* which are made of a form somewhat similar to ordinary safety pins, but which comprise a main 60 loop member having ends *c*² that are folded in the same direction and in the same plane to form inwardly directed parts *c*³ parallel with the main back parts *c*⁴, and one of the parts *c*³ is extended to form a pin *c*⁵ which 65 projects beyond the opposite end of the body portion of the pin device and is provided at its inner end portion with a collar *c*⁶. In the use of these pin devices in securing the collaret to the garment, the 70 said pin devices are employed longitudinally of the collaret and in the central longitudinal spaces *b*⁷, and the pin members *c*⁵ are passed through the central part *b*⁵ of the collaret and through the garment, as 75 clearly shown in Fig. 4, and in this operation the points of the pin members *c*⁵ of the pin devices project beyond the corresponding ends of the bodies of the pin devices, or the inwardly directed hook members *c*³ 80 thereof, and said inwardly directed hook members *c*³ and the collars *c*⁶ on the pin members *c*⁵ hold the pin devices in position and prevent their longitudinal movement, and said pin devices cannot be detached, except by hand, as will be readily understood. Any desired number of these pin devices may be employed and by means thereof the 85 collaret or facing may be secured to a garment of any kind or class, whenever desired, and detached therefrom whenever necessary, and by reason of the construction employed the collaret is reversible and may be used with either side out or either edge up, or in other words my collaret may 90 be used in four different positions.

My improved collaret or facing may be made of any preferred material, and changes in and modifications of the construction herein described may be made, within the 100 scope of the appended claim, without departing from the spirit of my invention or sacrificing its advantages.

Having fully described my invention, what I claim as new and desire to secure by 105 Letters Patent, is:—

A reversible collaret or facing of the class described composed of two similar side strips folded centrally and longitudinally, and a central reinforcing and connecting 110 strip placed between the folds of the side strips, the folded edge portions of the side

strips being folded inwardly and stitched longitudinally to the central reinforcing and connecting strip, and said folded edge portions of the side strips forming narrow central longitudinal spaces exposing the central reinforcing and connecting strip on both sides of the collar.

In testimony that I claim the foregoing

as my invention I have signed my name in presence of the subscribing witnesses this 10 14th day of July 1915.

CARL ILIGAN.
